UNITED STATES PATENT OFFICE.

ALBERT TILT, OF MONTCLAIR, NEW JERSEY.

CUTTING ATTACHMENT FOR LOOMS.

No. 851,570.

Specification of Letters Patent.

Patented April 23, 1907.

Application filed September 22, 1906. Serial No. 335,674.

To all whom it may concern:

Be it known that I, ALBERT TILT, a citizen of the United States, residing in Montclair, Essex county, State of New Jersey, have invented certain new and useful Improvements in Cutting Attachments for Looms; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 My invention relates to looms for weaving plural-width fabrics, and it has reference particularly to the mechanism, commonly associated with such looms, for cutting or dividing the fabric into the respective portions 20 thereof.

25 My invention comprehends the use of a movable blade, and it distinguishes from previous devices having movable blades in that the blade moves in substantially the direction in which its edge extends and at an angle to the plane of the goods, which feature I find is of great value in insuring a straight, true cut and the avoiding, thus, of damage to the inside selvages of the goods. It 30 should be understood, however, that my invention is not limited to this feature in its every aspect, as certain other features thereof are new in themselves, to the best of my present knowledge.

35 I have illustrated my invention in full in the accompanying drawings, wherein,

Figure 1 shows it applied to a loom, the whole being shown in side elevation; Fig. 2 is a top plan view of what is seen in Fig. 1; 40 Fig. 3 is a perspective view; and, Fig. 4 is a sectional view on line x—x in Fig. 3.

In said drawings, the loom frame a, cloth roller b, sand-roller c, breast-beam d, metal breast roller e, batten f, lay-swords g, rock-shaft h, shuttle i, reed j and harness j' are or 45 may be constructed and arranged substantially as in ordinary looms.

On the breast-beam and at suitable intervals, for instance, at both ends thereof, are 50 placed brackets k in which are journaled the trunnions or reduced end portions l of a shaft m. This shaft carries two arms n projecting toward the front of the loom, horizontally, and having their free ends upturned, 55 as at o. On the upturned ends of said arms is mounted a rod p having holes q to receive

said ends of the arms. This rod forms a support for the cutters shown in Figs. 3 and 4, each of which consists of a blade r having a sleeve s penetrating the same in its upper portion and at right angles thereto. As many of these cutters as are needed, according to the number of sections of goods to be woven, are mounted on the rod p, which may be removed from the arms n to permit the sleeves 60 s to be slipped over it.

The relative form and arrangement of the brackets, shaft m, rod p, the cutters and the roller e are such that the cutters hang with their cutting edges t substantially vertical 70 and their opposite edges in the lower portion thereof against the roller e, which roller resists the tendency of the cutters to turn on the rod p under the pull of the cloth. The blades r should be made somewhat wide, as 75 shown, so that a broad bearing surface will be presented to the already-cut edges of the goods and thereby insure a straight cut.

On the rock shaft h is arranged an arm u which is connected by a pitman v with a bent 80 crank w secured to the rock-shaft m.

In the operation of the loom, as the goods advances and is drawn against the blades r, which are held from receding by the roller e as above described, said blades move vertically, i. e., substantially in the direction in which the edge t of the blade extends, and since this is at an angle to the plane of the goods, the blades cut the goods evenly, avoiding the wavy cut which has been observed in 90 the use of previous devices of this kind and which often results in damaging the selvage. The cutters being, as shown, arranged so as to slide laterally on the rod p, I am enabled to very conveniently set each at the precise 95 point at which it is needed.

Having thus fully described my invention, what I claim as new and desire to secure by Letters Patent is:

1. In a loom, the combination, with the 100 frame, of means for controlling the warp and weft in the weaving operation, a cutter having its cutting edge disposed at an angle to the cloth plane, and means for moving the cutter in substantially the direction in which 105 its cutting edge extends, substantially as described.

2. In a loom, the combination, with the frame, of means for controlling the warp and weft in the weaving operation, a cutter having its cutting edge substantially straight and 110 disposed at an angle to the cloth plane, and

means for moving the cutter in substantially the direction in which its cutting edge extends, substantially as described.

3. In a loom, the combination, with the frame, of means for controlling the warp and weft in the weaving operation, a cutter having its cutting edge disposed at an angle to the cloth plane, and means for moving the cutter, substantially rectilineally, in substantially the direction in which its cutting edge extends, substantially as described.

4. In a loom, the combination, with the frame, of means for controlling the warp and weft in the weaving operation, a cutter, a going part, a rocking structure carrying said cutter, and means for operatively connecting said structure with the going part, substantially as described.

5. In a loom, the combination, with the frame, of means for controlling the warp and weft in the weaving operation, a rocking structure comprising a substantial horizontal rod, a cutter pivoted on said rod and depending therefrom through the cloth plane, means for holding the cutter against pivotal movement on said rod under the pull of the cloth, and means for rocking said structure, substantially as described.

In testimony, that I claim the foregoing, I have hereunto set my hand this 14th day of September, 1906.

ALBERT TILT.
